DESIGN FOR AN APPLIQUÉ EMBLEM OR SIMILAR ARTICLE

Walter P. Burn, Washington, D. C., assignor to the United States of America

Application September 8, 1941, Serial No. 103,232

Term of patent 7 years

To all whom it may concern:

Be it known that I, Walter P. Burn, a citizen of the United States and a resident of Washington, in the District of Columbia, have invented a new, original, and ornamental Design for An Appliqué Emblem or Similar Article, of which the following is a specification, reference being had to the accompanying drawing, forming part hereof.

Fig. 1 is a front elevational view of an appliqué emblem showing my new design;

Fig. 2 is an edge view thereof.

While I have shown my design in the form of an appliqué emblem it is understood that the same may be embodied in other similar articles such as badges, placards, banners, buttons, pins, arm pieces, and the like without departing from the spirit of my invention.

I claim:

The ornamental design for an appliqué emblem or similar article, as shown and described.

WALTER P. BURN.
